UNITED STATES PATENT OFFICE.

LEON J. LE PONTOIS, OF LAKWOOD, OHIO; ANNA LE PONTOIS, ADMINISTRATRIX OF
SAID LEON J. LE PONTOIS, DECEASED, ASSIGNOR TO THE TEAGLE COMPANY, OF
CLEVELAND, OHIO, A CORPORATION OF OHIO.

ELECTRIC GENERATOR.

1,422,584.

Specification of Letters Patent. Patented July 11, 1922.

Application filed March 28, 1917. Serial No. 158,094.

To all whom it may concern:

Be it known that I, LEON J. LE PONTOIS, a citizen of the Republic of France, residing at Lakewood, in the county of Cuyahoga and State of Ohio, have invented certain new and useful Improvements in Electric Generators, of which the following is a specification; reference being had therein to the accompanying drawing.

10 This invention relates to improvements in electric generators and more particularly to inductor alternators especially adapted for ignition purposes in connection with internal combustion engines.

15 The general object of the invention is the provision of apparatus of the character referred to highly efficient and reliable in operation and characterized by simplicity and ruggedness of construction and low cost of 20 production.

The expedients which I have devised to these ends will readily be understood from the following description in which I set forth, in connection with the accompanying 25 drawings, a preferred embodiment of the invention.

In the drawings

Figure 1 is a central vertical longitudinal section of an electric generator embodying 30 my invention;

Fig. 2 is a fragmentary section through one of the distributor segments;

Fig. 3 is a section on the line *a—a* of Fig. 1;

35 Fig. 4 is a section on the broken line *b—b* of Fig. 1;

Fig. 5 is a detail view of one of the distributor parts.

Fig. 6 is a diagrammatic view of the generating wiring and a circuit in which the 40 generator may be used.

Referring in detail to the construction illustrated, 1 indicates as an entirety a rectangular frame structure. This structure 45 preferably comprises a combined base and pole piece 2 of soft iron having a polar face 2^a, an upper pole piece 3 of soft iron, and end plates 4 and 5 of non-magnetic material. The pole pieces 2 and 3 and the end plates 50 4 and 5 are rigidly united by screws 6 and dowel pins 7. The pole piece 3, which is preferably cored out as indicated to avoid superfluous metal, has laminated pole ex-

tensions 8 and 9 with polar faces 8^a and 9^a, respectively. These pole extensions are preferably formed by a series of soft iron laminae 10 which are rigidly united by rivets 11. The pole piece 3 is formed with depending undercut flanges or extensions 3^a and the laminae 10 are correspondingly notched 60 to enter between said flanges with a driven fit and form a tight and rigid dove-tailed connection between the parts.

12 indicates as an entirety an inductor rotor mounted to turn about the longitudinal axis of the polar faces 2^a, 8^a and 9^a. The rotor comprises a shaft section 13 and a laminated flux distributing section 14. The latter section is made up of a series of soft iron laminae 14^a keyed upon the shaft and rigidly held between end plates 15 and 16, the plate 15 bearing against a shoulder on the shaft 13 while the plate 16 is secured in position by a pin 17. The rotor is operatively mounted in antifriction bearings 18 and 19 which are mounted respectively in the end plates 4 and 5. The outer ball race of the bearing 18 bears against a shoulder 4^a of the end plate to take end thrust in one direction while the outer ball race of the bearing 80 19 bears against a threaded disk 20 which takes thrust in the opposite direction. The disk 20 also serves to close the bearing 19 and prevent the escape of lubricant outward. The screws 6 and dowel pins 7 hold the end 85 plates 4 and 5 and the pole pieces 2 and 3 rigidly in accurately fixed relation so that the machining of the end plates and of the polar faces to secure the accurate alignment of the bearings 18 and 19 with each other 90 and with the polar faces, is readily accomplished.

On the opposite sides of the frame structure 1 are arranged permanent magnets 21, with their upper ends in consequent pole relation with the pole piece 3 and their lower ends in consequent pole relation with the pole piece 2. The magnets may be secured to the pole pieces 2 and 3 in any suitable manner, as by screws 22. These 95 magnets 21 are preferably plain straight bar magnets. The number of magnets can be varied but the construction shown contemplates four magnets, two on each side of the frame 1, the combined width of two magnets being equal to the length of the pole 100 105

pieces 2 and 3 so that when the magnets have been attached to the pole pieces they serve, in connection with the frame structure 1, to completely enclose the interior parts 5 of the generator. At the same time said magnets are in no sense a part of the supporting frame structure 1 which is self-contained and stands alone on its own bottom independently of the magnets 21.

10 On the pole extension 8 is mounted a generating coil 23 comprising an inner section 23^a of relatively coarse wire and an outer section 23^b of relatively fine wire, see Fig. 6. These windings may, for convenience, 15 be referred to as the primary and secondary windings, respectively. One terminal of the primary winding 23^a may be connected to ground while the other terminal of said winding is connected with a breaker mechanism for opening and closing the primary 20 circuit.

The said breaker mechanism comprises parts as follows: 25 is a cam on the rotor shaft 13 and 26 is a cam lever pivotally mounted at one end on a stud 27 and formed intermediate its ends with a block 26^a arranged to engage the cam surfaces of the cam 25. At its free end the arm 26 carries an electrode 28 arranged to engage an 30 electrode 29 adjustably mounted on one of the outwardly turned ends of the arcuate supporting plate 30 which in turn is riveted to, but electrically insulated from the annular plate 31. The other outwardly turned 35 end of plate 30 carries a binding post 30^a for an insulated conductor leading to one of the terminals of the primary winding 23^a. The plate 31 is secured by screws 31^a to the end plate 5 of the main frame. The lever 40 arm 26 is secured in position on the pivot stud 27 by means of a clip 32 and said arm is yieldingly pressed toward the cam 25 by the torsion spring 33. When the cam 25 turns with the rotor, the electrode 28 on the 45 lever arm 26 is moved into and out of engagement with the fixed electrode 29 to close and open the primary circuit. The circuit closing and opening mechanism is preferably enclosed by a cap or cover 34 secured in position by clip 35.

The circuit of the fine wire winding of the generator coil is controlled by suitable distributor mechanism. In the preferred form of construction illustrated, the end 55 plate 5 is recessed to receive a driving pinion 36 mounted on the rotor shaft 13 and a gear 37 driven by the pinion 36 and fixedly mounted on the inner end of a hollow shaft 38 which is rotatably mounted in a bearing 39 formed in the end plate 5. The outer end of shaft 38 is circumferentially grooved to receive a clip ring 40 which secures the shaft against displacement. Fixedly mounted in the hollow shaft 38 is an insulation block 60 65 41 which comprises a hub section 41^a and

a radial arm section 41^b. In the axis of the hub section 41^a is arranged a conductor 42 which is conducted at its inner end with a tubular socket 43 in which is mounted a brush 44 pressed by spring 45 into engagement with the terminal plate 46 of the fine wire winding 23^b of the generating coil. At its inner end the conductor 42 is electrically connected to the inner end of a radial conductor plate 47, which, at its outer end, 70 is connected to the tubular socket 43 in the outer end of the insulation arm 41^b. In this socket is mounted a brush 49 which is pressed yieldingly outward by a spring 50. 75 51 is a combined distributor block and cover 80 formed of suitable insulating material and shaped to fit closely an annular flange 5^a of the end plate 5. The distributor block carries a suitable number of contact segments 52 which are engaged in the well 85 known manner by the moving brush 49 of the distributor. In the present case there are four of the contact segments 52 and each may be suitably connected with a conductor leading to one of the spark plugs of 90 an engine in the well known manner.

The distributor cover 51 may be secured in position in any suitable manner, as by the fingers or clips 53 which are pivotally connected at 54 to the face plate 5 and have resilient hook-shape ends that engage suitable notches (not shown) in the front face of the block 51.

55 is a conductor plate secured to and grounded on the pole piece 3 so that it is disposed adjacent and spaced from the terminal plate 46 of the generating coil to provide a safety spark gap.

56 is a condenser of any suitable construction mounted on the pole extension 9, being secured thereto in any suitable manner.

Referring to the diagram of the electrical connections in Figure 6, it will be observed that the primary winding 23^a of the generating coil has one of its terminals connected 110 to ground through a switch 57 while its other terminal is connected to the stationary electrode 29 of the circuit closing and opening mechanism. The movable electrode 28 is connected to ground (through the frame 115 of the machine) and the condenser 56 is connected, in the usual manner, in parallel with the electrodes 28 and 29. The secondary winding 23^b of the generating coil has one of its terminals connected to one of the 120 terminals of the primary winding 23^a while its outer terminal is connected with the moving element of the distributor mechanism. At 58 I show a battery one terminal of which is grounded and the other of which is arranged to be connected, when desired, through switch 57 with the primary winding 23^a of the generating coil.

The operation of the generator will be readily understood by those skilled in the 130

art from an inspection of the drawings, and a brief description will therefore suffice. Assuming that the rotor 12 occupies the position illustrated in Figure 3 of the drawings, 5 and is rotating counterclockwise as indicated by the arrow, it will be seen that the entire flux of the magnets, except, of course, for inevitable leakage, is passing through the pole extension 8 which, in effect, constitutes the 10 core of the generating winding. As the rotation continues the forward edge of the upper side of the flux distributing section of the rotor comes adjacent the pole extension 9 and a portion of the magnetic flux 15 then begins to flow through the latter extension, the flux through the generating coil being correspondingly diminished. Approximately at the point when the decrease of flux through the generating coil reaches 20 a maximum, the breaker cam 25 acts to break the primary circuit of the coil whereupon a high tension current is generated in the secondary winding of the coil, said current being reinforced by the continued decrease of 25 the magnetic flux through the coil incident to the continued rotation of the rotor. As said rotation continues, the lower side of the flux distributing section of the rotor leaves the polar face of the pole piece 2 and its forward edge comes adjacent the pole extension 8 while the other side of the flux distributing section in turn comes adjacent the polar face 30 of the pole piece 2. In this way the magnetic flux is again established through the 35 pole extension 8, and the operation of the circuit breaker is so timed that the primary circuit remains open until the increase of flux through the pole extension 8 has ceased whereupon the primary circuit is again 40 closed through the breaker electrodes 28 and 29. Then with continued rotation the cycle of operations is repeated. The distributing mechanism is of course synchronized with the breaker and rotor so that the 45 distributor brush 49 is in contact with one of the segments 52 when the high tension current is induced in the secondary winding.

The generator, as illustrated, is intended 50 for use with a four-cylinder internal combustion engine, being adapted, when the generator is driven at crank shaft speed, to give two sparks per revolution. It will be understood that any suitable gearing may be 55 provided for driving the generator from the engine and, if desired, use may be made of one of the well known forms of coupling devices adapted, either automatically or under manual control, to advance and retard the spark 60 by effecting an angular advance or retardation of the rotor in relation to the crank shaft of the engine.

When the generator is used for starting an engine, the battery can be employed if 65 desired to energize the primary winding,

care being taken that the battery is connected in circuit so as not to de-energize the permanent magnet.

I have explained that the primary circuit is never closed while the magnetic flux 70 through the generating coil is increasing but that the current induced in the primary winding is always due to decrease of flux through said winding; and inasmuch as the generating windings are fixed in relation to 75 the permanent magnets, it follows that the magneto-motive force generated by the current induced in the primary winding, and also by the current induced in the secondary winding by the interruption of the primary 80 circuit, always acts with the magneto-motive force of the permanent magnets and not against it. Hence, by reason of this constant electro-magnetic relationship of the path of least reluctance between the poles 85 of the permanent magnets and through the generating windings, the permanent magnets are never subjected to demagnetizing action in the operation of the generator.

This constant electro-magnetic relationship which characterizes my improved generator not only tends to maintain the maximum efficiency and capacity of the generator, but makes possible also other notable advantages. Thus, by reason of this characteristic of the magnetic circuit, I have found 90 it possible to employ material for the permanent magnets having a relatively low coercive force and to use magnets of a length not exceeding the height of ignition current 95 generators complying with standardization requirements. In other words, I am enabled to use a relatively cheap material for the permanent magnets and to make them in straight bar form with a minimum amount 100 of fabrication so that their cost of production is exceedingly low.

In addition, the form of magnet thus made possible in turn gives rise to advantages of great practical importance. That is 110 to say, these straight bar magnets lend themselves admirably to use in connection with a main supporting frame such as has been described. In this frame the lower pole piece and base, the upper pole piece and the two 115 end plates, all rigidly connected, form a structure closed on four sides, and the plain bar magnets, of a length not exceeding the height of the supporting frame, are readily applied, by simple attaching means, so as 120 to entirely close the chamber within the frame structure so that the interior working parts are provided with a dust and water tight casing. Furthermore, with the straight bar magnets assembled in this manner, it 125 is possible to machine the bottom pole piece to fit and be secured to a standard magneto support. And as the straight bar magnets support none of the other parts of the mechanism, they can at any time be readily re- 130

moved to expose the interior parts for inspection or repair.

I have already referred to the constant electro-magnetic relationship of the fixed path between the poles of the permanent magnets as a factor in the maintenance of the efficiency and capacity of the generator. It is to be noted further in this connection that the magnetic flux through the pole pieces and polar projections, including the polar projection 8 which constitutes the core of the generating coil, is unidirectional so that heat losses in these iron parts are minimized and the efficiency correspondingly increased.

The simplicity of the rotor and its comparatively light weight, besides making alignment easy, puts very little wear on the bearings and make possible exceedingly high speed operation.

Since the generating coil is stationary, it can be grounded on the stator so that no current passes through the bearings and, also, much more space is available for the generating coil and the condenser than would be available if they were mounted on the rotor, so that ample insulation may be used without exceeding the standard magneto height.

A distributor mechanism constructed as herein set forth can be made absolutely water tight, and, at the same time, the interior parts can be exposed by simply swinging back the hinged fingers or clips 53 and removing the block and cover 51.

The breaker mechanism is readily exposed for repair or adjustment by simply swinging aside the clip 35 and removing the cover 34.

While I preferably prevent a demagnetizing effect upon the straight bar magnets by controlling the circuit of the generating winding as above set forth, the invention is not to be understood as limited to that precise manner of circuit control, for I believe that I am the first to provide an ignition generator having pole pieces, end plates, straight bar magnets, generating winding and rotor, as above described, and means for controlling the circuit through the generating winding adapted, when the rotor is driven at a uniform speed, to open or close the circuit in such manner that the net effect on the magnets of the reaction of the winding is a magnetizing effect. In other words it is to be understood that the advantages of my invention can be secured in a substantial measure even if the magneto-motive force incident to the reaction of the generating

winding is opposed to the magneto-motive force of the magnets during a part of the cycle of operations providing that during other parts of said cycle there is a superior magneto-motive force incident to the winding reaction in the same direction as the

magneto-motive force of the magnets so that the net effect of the reaction of the winding on the magnets tends to magnetize the latter and thus to fully maintain their strength.

To those skilled in the art it will be apparent that I have provided a generator with a very small number of parts and also that the individual parts are exceedingly simple and substantial and capable of production with precision by economic methods. It will also be seen that the structure is easily assembled.

It will be understood that the structure which has been particularly described may be varied in various respects without departing from the invention and that said structure has been set forth in detail for purposes of explanation and illustration and is not to be construed in a limiting sense.

In so far as the subject-matter herein-after claimed is common with the disclosure in my earlier applications, Serial No. 596,117, filed December 7, 1910, and Serial No. 627,927, filed May 18, 1911, I hereby elect to treat this application as a continuation of the said earlier ones.

What I claim is:

1. In an ignition current generator, the combination of a bottom pole piece of cast iron formed on its top side with a polar surface and on its bottom side formed to rest upon and be secured to a suitable support for the generator, a top pole piece comprising a cast iron block and a plurality of bifurcated laminæ secured thereto and forming depending polar projections with polar surfaces at their lower ends opposite the polar surface of the bottom pole piece, non-magnetic end plates rigidly attached to the said pole pieces and forming therewith a rigid supporting frame, permanent magnets in the form of straight bars disposed on opposite sides of said supporting frame with their north pole ends abutting one pole piece and their south pole ends abutting the other pole piece, a generating winding in inductive relation to one of said polar projections, and an unwound inductor rotor operably mounted in said end plates and shaped and correlated to said polar surfaces of the poles alternately to establish a flux path through said winding and then a path outside of said winding.

2. In an ignition current generator, the combination of a bottom pole piece of cast iron formed on its top side with a polar surface and on its bottom side formed to rest upon and be secured to a suitable support for the generator, a top pole piece comprising a cast iron block and a plurality of bifurcated laminæ secured thereto and forming depending polar projections with polar surfaces at their lower ends opposite the polar surface of the bottom pole piece, non-magnetic end plates rigidly attached to opposite sides of

the said pole pieces in planes substantially parallel with the laminæ of the said depending polar projections and forming with said polar pieces a rigid supporting frame, permanent magnets in the form of straight bars disposed on opposite sides of said supporting frame with their north pole ends abutting one pole piece and their south pole ends abutting the other pole piece, a generating winding in inductive relation to one of said polar projections, and an unwound inductor rotor operably mounted in said end plates and shaped and correlated to said polar surfaces of the poles alternately to establish a flux path through said winding and then a path outside of said winding.

3. In an ignition current generator, the combination of a bottom pole piece of cast iron formed on its top side with a polar surface and on its bottom side formed to rest upon and be secured to a suitable support for the generator, a top pole piece comprising a cast iron block and a plurality of bifur-

cated laminæ rigidly secured to the under side of said block by a forced fit dove-tail connection and forming depending polar projections with polar surfaces at their lower ends opposite the polar surface of the bottom pole piece, non-magnetic end plates rigidly secured to the pole pieces in planes parallel to the said laminæ and forming with the pole pieces a rigid supporting frame, permanent magnets in the form of straight bars disposed on opposite sides of said supporting frame with their north pole ends abutting one pole piece and their south pole ends abutting the other pole piece, a generating winding in inductive relation to one of said polar projections and an unwound inductor rotor operably mounted in said end plates and shaped and correlated to said polar surfaces of the poles alternately to establish a flux path through said winding and then a path outside of said winding.

In testimony whereof, I affix my signature.

LEON J. LE PONTOIS.
